Primary Examiner — Cynthia Underwood

(74) *Attorney, Agent, or Firm* — Ladas & Parry LLP

(57) **CLAIM**

The ornamental design for a clip, as shown and described.

DESCRIPTION

FIG. 1 perspective view viewed from the top side of a clip showing our new design;

FIG. 2 is a perspective view viewed from bottom side thereof;

FIG. 3 is a front elevation view thereof;

FIG. 4 is a right side elevation view thereof;

FIG. 5 is a top plan view thereof;

FIG. 6 is a bottom plan view thereof;

FIG. 7 is a cross-sectional view taken along line 7-7 in FIG. 3;

FIG. 8 is a cross-sectional view taken along line 8-8 in FIG. 4; and,

FIG. 9 is a perspective view from the top side shown reduced in scale and in an environment of use, the broken lines forming no part of the claim.

The broken lines shown in the drawings represent unclaimed portions of the clip and form no part of the claimed design.

1 Claim, 4 Drawing Sheets
